AUTOMATIC LAWN SPRINKLER OR THE LIKE

Isaac Rinkewich, 290 9th Ave., New York, N.Y.

Filed Dec. 24, 1964, Ser. No. 83,146

Term of patent 14 years

(Cl. D91—1)

FIG. 1 is a perspective view of an automatic lawn sprinkler looking down on the rear quarter thereof, embodying my new design;

FIG. 2 is a perspective view thereof, looking down on the front quarter; and

FIG. 3 is a bottom plan view thereof.

The essential features of my design reside in those features shown in full lines.

I claim:

The ornamental design for an automatic lawn sprinkler or the like as shown and described.
